UNITED STATES PATENT OFFICE.

RICHARD MIDDLETON SIMPSON, OF WELLINGTON, NEW ZEALAND.

POSTMARKING-MACHINE.

1,299,249.

Specification of Letters Patent.

Patented Apr. 1, 1919.

Application filed February 21, 1916. Serial No. 79,792.

To all whom it may concern:

Be it known that I, RICHARD MIDDLETON SIMPSON, a subject of the King of Great Britain, residing at 5 Upland road, Kelburn, in the city of Wellington, Dominion of New Zealand, have invented certain new and useful Improvements in Postmarking-Machines, of which the following is a specification.

10 This invention relates to the separating and enumerating mechanism of postmarking or mailmarking machines.

By this invention the separation and enumeration of letters is effected with great 15 accuracy and rapidity.

The separator consists broadly of a horizontally disposed band or series of bands preferably of rubber or a material of similar friction or retarding surface supported 20 on a frame arranged to rock horizontally with an adjusting attachment for tension of bands.

In the accompanying drawings illustrating this invention—

25 Figure 1 is a plan showing the separator and enumerator in position on a mailmarking table.

Fig. 2 is an enlarged plan of the separator.

30 Fig. 3 is a sectional elevation of the separator on line A—A Fig. 2.

Fig. 4 is a front elevation of the separator showing a band in position.

Fig. 5 is an enlarged plan showing the 35 method of securing the bands.

Fig. 6 is a side elevation of the enumerator and rollers.

Fig. 7 is a cross section through line B—B of Fig. 6.

40 Fig. 8 is a sectional plan of the enumerating spider.

Fig. 9 is a sectional elevation on line C—C of Fig. 8.

Fig. 10 is a cross section of the upper 45 part of the type head, showing the pulley portion separate from the type head.

Fig. 11 is a perspective view of the separator and the enumerator in position.

The separator consists of a frame made 50 up of two similar bow shaped portions 1, 2, of which the opposite ends are connected by bars 3, 4, preferably square in cross section. The bar 4 is surrounded by rubber tubing 6 to prevent the slipping of the bands of rubber or other retarding material which are 55 placed around these bars. These bands are

also placed around a loose bar 5 (see Fig. 5) which is preferably square in cross section and is surrounded by a rubber tube 6^a said bar 5 being adapted to be placed in notches 60 8, 9, 10 for tensioning of the band at different tensions. The frame is pivotally secured by a pivot 9^a situated nearer one end of the frame than the other to a bracket 10 which has a slot 11 in which a set screw 65 is used to secure the bracket to the mailmarking table in different positions. A spring 12 connects the notched end of the frame to a projection 13 on the bracket 10.

The enumerator consists of a hub 14 in 70 which are fixed the ends of the preferable watch spring legs 15, 16, 17, 18 which have curved ends 19, 20, 21, 22 and terminate in knobs 23, 24, 25, 26. The fixed ends of the legs are reinforced by pieces of preferably 75 watch spring 27, 28 on each side. Disks 29, 30 are secured one on each side of the hub 14 by screws (see Fig. 9). The hub revolves with a spindle 31 the upper end of which is journaled in a plate 50 and through 80 bevel gearing 44 operates a spindle 44^a, this spindle being connected to a counting and indicating device of any suitable form, which device is operated to count and indicate at each quarter revolution of the 85 spindle 31. The bottom disk 30 of the hub revolves on a disk which is supported by a bracket 53.

The separator is adjusted so that its retarding surface makes an angle of about 15° 90 with the letter path 32 on marking table 43, its forward edge 33 just projecting over the letter path but not touching a feed roller 34. Adjoining this feed roller 34 is another feed roller 35 and co-operating therewith a 95 pressure roller 36. A pair of preferably rubber belts 37, 38 connect the feed roller 35 with the pressure roller 36 running in grooves in both rollers so that the inner faces of the belts lie in the letter path, leaving a space between them vertically. A similar pair of belts 39, 40 connect pressure roller 36^a with a pulley 50' on the top of the marking roller 41 in the same way. An inking roller 42 is provided to ink the type 100 head 41. The legs of the enumerator project into the letter path between the belts, see 105 Fig. 11.

In operation the letters after being faced with the stamped end downward are fed between the feed roller 34 and the retarding surface 7 of the separator from whence they 110

are flicked forward one by one by the revolution of the roller 34 between the rollers 35 and 36^a by the revolution of which they are sent forward being kept upright by and between the bands 37, 38, 39, 40. The foremost letter impinges on the end 26 of a leg of the enumerator and carries it forward until it is moved out of the letter path thus counting one. The next leg 23 is simultaneously brought forward and at first presses against the first letter and is thereby bent backward out of the letter path but when this first letter has passed on, the end of the leg springs quickly forward across the letter path and comes into position to be operated on in the same way by the next letter. The letters are sent forward by the impetus already given them to be stacked or otherwise dealt with in any known suitable manner.

The separator will require a little adjustment as regards angle with the letter path and position of its forward edge in respect of the feed roller 34 but the best position so far discovered with the rollers shown is as above described.

I claim:

1. A mail separating device comprising in combination a friction roller, and a retarding device coöperating therewith consisting of a supporting member having flexible means stretched between two spaced points of said member, said flexible means being substantially tangential to the surface of said roller.

2. A mail separating device comprising in combination a friction roller and a retarding device coöperating therewith consisting of a supporting member having a plurality of flexible bands stretched between spaced points of said member to provide a flexible surface said surface being substantially tangential to the surface of said roller.

3. A mail separating device comprising in combination a friction roller and a retarding device coöperating therewith consisting of a supporting member having flexible means adjustably stretched between spaced points of said member, said flexible means being substantially tangential to the surface of said roller.

4. A mail separating device comprising in combination a friction roller, a retarding device coöperating therewith consisting of a bow shaped frame, and flexible means stretched between the ends of said frame, the surface of said flexible means being substantially tangential to the surface of said roller.

60 5. A mail separating device comprising in combination a friction roller, a retarding device coöperating therewith consisting of a frame, bars carried by said frame and spaced from each other, flexible means stretched between said bars to form a flexible plane

surface tangential to the surface of said roller, and means permitting variation of the distance between said bars to vary the tension of said flexible means.

6. A mail separating device comprising in combination a friction roller and a retarding device coöperating therewith consisting of a pivotally mounted member having flexible means stretched between spaced points thereof to provide a plane surface substantially tangential to the surface of the roller.

7. A mail separating device comprising in combination a friction roller and a retarding device coöperating therewith consisting of a pivotally mounted member having a plane surface tangential to the surface of said roller and movable about its pivot to permit passage of a letter, and resilient means resisting such movement of the member.

8. A mail separating device comprising in combination a friction roller and a retarding device coöperating therewith consisting of a pivotally mounted bow-shaped frame having a plurality of flexible bands stretched between the ends thereof to provide a plane surface substantially tangential to the surface of said roller, and movable about its pivot to permit passage of a letter, and resilient means resisting such movement of the frame.

9. A mail separating device comprising a friction roller, and a bow-shaped pivotally mounted frame having friction bands thereon to provide a surface adjacent to and co-operating with the surface of the roller, and means for varying the tension of said bands.

10. A mail separating device comprising a friction roller, a frame having bands thereon, the plane of said band surface being substantially tangential to the surface of the roller, and means for moving said frame toward or away from the axis of the roller, for the purpose set forth.

11. The combination with a mail separating device and a marking roller, of conveyer means consisting of a plurality of parallel belts engaging the opposite sides of the letter, certain of said belts frictionally engaging and directly driving said roller.

12. A mail separating device comprising a friction roller, a bow-shaped pivotally mounted frame carrying bars, friction bands mounted on said bars to provide a surface adjacent to and co-operating with the surface of the roller, and means for varying the tension of said bands consisting of spaced notches in said frame for receiving one of said bars.

13. The combination with a mail separating device comprising a friction roller, a bow-shaped pivotally mounted frame having friction bands thereon co-operating with said roller, and means for varying the tension of said bands, of conveyer means con-

sisting of a plurality of parallel belts engaging opposite sides of the letter.

14. The combination with a mail separating device, of a pressure roller opposed by a feed roller, another pressure roller opposed by a marking roller, a belt running around said first named pressure roller and said marking roller to directly drive the latter, another belt running around said second named pressure roller and said feed roller, the proximate surfaces of said belts providing a letter path tangential to the marking surface of said roller.

15. A mail separating device comprising a feed roller, means for holding a block of laminated pieces adjustably engaging their

ends obliquely, a pressure roller opposed by a feed roller, another pressure roller opposed by a marking roller, a belt running around said first named pressure roller and 20 said marking roller to directly drive the latter, another belt running around said second named pressure roller and said feed roller, the proximate surfaces of said belts providing a letter path tangential to the marking 25 surface of said roller.

In testimony whereof he has affixed his signature in presence of two witnesses.

RICHARD MIDDLETON SIMPSON.
